(57) **CLAIM**

The ornamental design for a shoe sole, as shown and described.

DESCRIPTION

FIG. 1 is a left side view of a shoe sole in accordance with our new design;

FIG. 2 is a right side view thereof;

FIG. 3 is a front view thereof;

FIG. 4 is a rear view thereof;

FIG. 5 is a top view thereof;

FIG. 6 is a bottom view thereof;

FIG. 7 is an enlarged view of the portion of the shoe sole shown within the area designated as 7 in FIG. 3;

FIG. 8 is an enlarged end view taken along line 8-8 of FIG. 6; and,

FIG. 9 is an enlarged view of the portion of the shoe sole shown within the area designated as 9 in FIG. 8.

The small dashed broken lines in the figures depict portions of the shoe sole that form no part of the claimed design. The larger dashed broken lines in the sectional views indicate surfaces that form no part of the claim. The peripheral dash dot dash broken lines in FIGS. 3, 7, 8, and 9 illustrate the cut line of the enlarged sectional views and form no part of the claim.
